United States Patent

Des. 242,186
Patented Nov. 2, 1976

242,186

INVERTIBLE SIGN

Elmer E. S. Lengyel, 4655 Wild Indigo #231,
Houston, Tex. 77027

Filed Sept. 7, 1973, Ser. No. 372,191

Term of patent 14 years

Int. Cl. D11—03; D18—03; D20—03
U.S. Cl. D96—12 E

The figure is a front view of an invertible sign showing my new design. The sign is of insubstantial thickness and the reverse side is identical to the side shown.

I claim:

The ornamental design for an invertible sign, substantially as herein shown and described.
